UNITED STATES PATENT OFFICE.

CHARLES H. TRASK, OF LYNN, MASSACHUSETTS.

HEEL-TRIMMING MACHINE.

SPECIFICATION forming part of Letters Patent No. 357,740, dated February 15, 1887.

Application filed June 15, 1886. Serial No. 205,203. (No model.)

To all whom it may concern:

Be it known that I, CHARLES H. TRASK, of Lynn, in the county of Essex and State of Massachusetts, a citizen of the United States, have invented a new and useful Improvement 5 in Heel-Trimming Machines, of which the following is a full, clear, and exact description, reference being had to the accompanying drawings, forming a part of this specification, in 10 explaining its nature.

The invention is an improvement upon that described in my application for Letters Patent of the United States executed June 2, 1886, filed June 7, 1886, Serial No. 204,324, and it 15 relates to various details of construction and organization, all of which will hereinafter be described.

In the drawings, Figure 1 is a front elevation of a machine containing the features of 20 my invention. Fig. 2 is a right side elevation thereof. Fig. 3 is a plan view of the machine. Fig. 4 is a vertical section, enlarged, of the heel-trimming cutter and adjacent parts. Fig. 5 is a view in elevation of the front part or 25 section of the heel-trimming cutter. Fig. 6 is a view in elevation of the rear section or part of the heel-trimming cutter. Figs. 7 and 8 are side elevations of the cutter, showing the two sections together in one view and slightly 30 separated in the other. Fig. 9 is a view in front elevation of the rand-cutter.

The sole-edge cutter A, the shank-edge cutter B, and the heel-edge trimmer or cutter C are supported upon their respective shafts, *a* 35 *b* *c*, which are carried by the bracket A', and are operated as described in my said application. The sole-edge cutter and the shank-edge cutter are mounted upon their shafts substantially as therein described. The heel- 40 edge cutter C is represented as made in two parts or sections—the rear part or section, C', and the front part or section, C². The rear section, C', is shaped as represented in Figs. 4, 6, 7, and 8. It is formed from a disk or circular blank or plate, *c'*, which has a series of 45 teeth or cutters, *c*², formed therein, to be of the same length, and preferably the thickness, of the disk or block; and it also has another series of teeth or cutters, *c*³, which are formed 50 to project laterally from the plate or disk *c'*, and these groups of teeth *c*² *c*³ are arranged in

relation to each other, so that the teeth *c*² are formed upon one half of the plate or disk *c'* and the teeth *c*³ are formed on the other or opposite half of the plate or disk *c'*. The section or part C² of the cutter is similar in general shape to the section C'—that is, it is also made from a blank having a disk or plate, *c*⁴, upon one side of which is formed the short teeth or cutters *c*⁵, and upon the other side of which is 60 formed the longer teeth or cutters *c*⁶, and when the two sections of the cutter are together the long teeth of one section form continuations of the short teeth of the other, as represented in Fig. 7. The surface of the cutter may have 65 any desired shape or curvature, and it is governed, of course, by the shape which it is desired to give the finished heel.

The rear section, C', has holes *c*⁷, for the reception of the screws *c*⁸, which lock it to the 70 collar *c*⁹, arranged to slide on the shaft *c*. This collar has a long sleeve, *c*¹⁰, which surrounds the shaft *c* and extends into the sleeve or box C³, and a recess, *c*¹¹, in which the top-lift rest and guide is movable, as hereinafter specified. 75 The section C² of the cutter is secured to the end of the shaft *c* against a shoulder, *c*¹², formed thereon by means of the screw-stud *c*¹³. The rand-cutter *c*¹⁴, and the rand-guard *c*¹⁵ are attached to the section C² of the heel trimmer or 80 cutter, as described in my said application, and are adjusted as therein set forth. The top-lift rest and guard D is suspended from the rod or stud *d*, which extends horizontally outward from the bracket A', and it is ar- 85 ranged to slide thereon, a wide bearing being provided by means of the sleeve *d*'. It is moved inwardly with the rear section, C', of the cutter, and away from the front section, C², of the cutter, by the pressure of the bottom of 90 the heel against the pressure of the spring *c*¹⁶, and this spring serves to return the top-lift rest and guide and the section C' of the cutter horizontally to their original position upon the removal of the heel, and also to keep the 95 top-lift rest constantly in contact with the bottom of the heel as the heel is being trimmed.

At the right side of the heel-edge cutter there is a heel-edge rest, E, which is carried by the rod *e*, which also supports the arm *e'*, 100 to which is attached the plate, bar, or rod *e*², for adjusting the rand-cutter B' of the shank-

edge cutter. The bar, rod, or support e' is made adjustable upon its supporting-arms e to move the rand guide and cutter of the shank-edge cutter.

5 In operation the sole and shank are trimmed substantially as described in my said application. In trimming the heel the bottom of the heel is placed upon the top-lift rest, with the edge of the top lift bearing upon the top-lift guide and the side of the heel-rest upon the surface of the heel, the rand-guard entering the crease above the rand. This placing of the heel moves the top-lift rest and guard and the section C' of the cutter to provide the cutter with a width or length sufficient to trim the section of the heel then presented to it. As the heel is moved the section C' is automatically moved outward by the work and inward by the spring, as the length of the surface 20 face of the heel to be trimmed varies.

Having thus fully described my invention, I claim and desire to secure by Letters Patent

of the United States—

1. The separable cutter C, made in two parts, 25 C' C², the part C' having the two groups of teeth c^2 c^3 and the part C² having corresponding

groups of teeth arranged in relation to the section C', so that its short teeth form continuations of the long teeth of said section, substantially as described.

2. The combination, in a heel-trimming machine, of the rotary cutter comprising the sections C' C², the stationary heel-rest E, and the non-rotating top-lift rest and guide D, substantially as described.

3. The combination of the heel-trimming-cutter C' C², the shank-edge cutter B, the rod or stud e , the heel-rest E, the arms e' , depending from said rest, and the rand-guard and shank-trimming cutter attached to said arms, 40 all substantially as described.

4. The combination, in a trimming-machine, of the section C² of a cutter, the independent rand-knife c^4 , the independent rand-guard c^5 , both attached to said section C² of the cutter, 45 to revolve therewith, and the section C' of the cutter movable to and from the section C², and a heel-rest, E, substantially as described.

CHARLES H. TRASK.
